Philadelphia, Pa., a corporation of Delaware

Application May 24, 1940, Serial No. 337,059
In Great Britain June 5, 1939

8 Claims. (Cl. 178—69.5)

This invention relates to synchronizing circuits and in particular to synchronizing circuits as used in connection with television receivers and the like. The invention has for its general object to provide a gas discharge tube oscillator adapted to synchronize in response to pulses included as a part of the composite television signal, and which is not appreciably affected in its operation by the presence of undesired noise pulses. Furthermore, the oscillator exhibits no appreciable tendency to "fire" or to be synchronized on pulses contained in the signal other than those on which it is intended to be so synchronized; for example, there is no tendency for the oscillator to be affected by the double frequency or "equalizing" pulses sometimes included in the television signal.

In copending application of Frank J. Bingley, Serial No. 224,646 filed Aug. 12, 1938, it is pointed out that oscillators of the class which includes the blocking oscillator and the like are characterized in that their cycles of operation may be divided into three periods, which may be referred to as the active, the passive and the inchoation periods. During the so-called inchoation period, the oscillator is subject to being fired by an incoming synchronizing pulse. During the active period, the tube which constitutes the heart of the oscillator is conducting and signals applied to the input are effective to influence the magnitude and energy content of the signal produced in the output circuit of the oscillator. During the passive period, the tube is cut off and is incapable of being fired by any signal of reasonable magnitude applied to its input. In the aforementioned application, there are disclosed certain methods of and means for preventing the signal developed in the output circuits of such oscillators from being influenced by noise and other signals applied to the input circuits during the active period. This is accomplished, in general, by feeding back a suitable signal from the output of the oscillator to block its input during the active period.

Further, in the said application it is observed that the principles might be extended and applied to synchronizable oscillators employing grid-controlled gas discharge tubes. In Fig. 13, of the said application for example, a circuit is shown in which a signal is derived from the output of a gas tube oscillator and applied to block the input of or to "quench" the tube during its conductive period, so that although ionic conduction continues to take place the grid is pre-

vented from exercising any control over the electron current in the tube.

Accordingly, by the present invention, there is provided in a synchronizable oscillator which employs a grid-controlled gas discharge tube to control the flow of current from an electrical circuit for generating a sawtooth or like wave form, means for quenching or blocking the input circuit of the gas tube whereby it is made entirely non-responsive to signals of reasonable amplitude during its active period as well as during its passive period, said means comprising an impedance inserted in the cathode circuit of the gas tube across which there is built up a voltage which is effective to bias the tube off at least throughout the active period.

The invention will be understood by reference to the drawing, the two figures of which show certain embodiments of the invention.

20 In Fig. 1 there is shown an oscillatory device for generating a voltage of substantially sawtooth wave form timed by means of substantially periodically recurrent pulse signals. The circuit comprises a condenser 3 which is charged by a battery 4 through a resistor 5. Effectively in shunt with the condenser there is provided a grid controlled gas discharge device 2 to the grid of which may be supplied from the source shown, the synchronizing pulses 1 for controlling the 25 operation of the oscillator. In the absence of synchronizing pulses, the oscillator just described will oscillate at a frequency determined by characteristics of the gas discharge device 2. The condenser will be charged to a point at which the 30 voltage on the plate of the gas discharge device is such as to cause it to conduct, at which time the condenser will be discharged through its discharge path. The potential at which the device conducts will be dependent upon the voltage applied between its grid and cathode. Thus when a synchronizing pulse of positive polarity 35 is applied to the grid of the tube the plate voltage necessary to cause the tube to conduct will be reduced to an extent dependent upon the magnitude of the pulse signal. Assuming that the 40 condenser has been charged for an appreciable time, a pulse signal may be applied to the grid of the tube which will cause the tube immediately to conduct and to discharge the condenser. There is also provided in the cathode circuit of the gas discharge device in accordance with the 45 invention an impedance comprising a resistor shunted by a condenser, for developing a voltage which is such as appreciably to reduce the controlling effect of the grid upon the operation

of the device during a part of the interval between the successive synchronizing pulses which it is desired should actuate the gas discharge device. If the condenser 9 is very small, for example not appreciably greater than the distributed capacity of the resistor 8, the voltage developed across the impedance combination will be a pulse signal substantially corresponding in duration to the current pulse in the gas discharge device occurring during the discharge of the condenser 3. Such a voltage pulse is adapted to reduce the controlling effect of the grid upon the current in the gas discharge device during this discharge period which is desirable since it will help to insure the peaks of the sawtooth voltage being of substantially constant amplitude. It may however be desirable to provide protection during a greater portion of the time interval between successive synchronizing pulses. With this in mind the condenser may be made larger whereby the voltage developed across the combination will be of substantially sawtooth form as indicated by the broken line at 10. Such a quenching voltage is adapted to reduce the susceptibility of the gas discharge device to actuation by extraneous pulse signals occurring between the desired synchronizing pulses. In particular it may operate to exclude the undesirable alternate double horizontal frequency pulses occurring before and after the vertical synchronizing pulse in the usual form of television synchronizing signal. In general the time constant of the combination comprising the resistor 8 and the condenser 9 should be of substantially the same order of magnitude as the time interval between successive synchronizing pulses. However it is to be understood that there may be considerable variation from this.

Other impedance combinations may be employed for the purpose of broadening the impulse of quenching voltage developed in the cathode and circuit. For example in Fig. 2 a resonant circuit comprising the inductance 13 and the condenser 14 is utilized for this purpose. It will be noted that the rest of the circuit is substantially the same as that shown in Fig. 1. When the gas discharge tube 2 is rendered conductive by means of a synchronizing pulse applied to its grid, the condenser 14 is suddenly charged to a positive potential with respect to ground. Then, when the tube 2 ceases to conduct due to reduction in its plate voltage brought about by the discharge condenser 3, the resonant circuit will be permitted to oscillate freely. The nature of the quenching voltage produced will of course be dependent upon the frequency to which the resonant circuit is tuned. If, for example, this frequency is appreciably less than the frequency of occurrence of the synchronizing pulses which it is desired should actuate the gas discharge device the quenching voltage may be of the form shown at 11. Although this voltage will have decreased sufficiently by the time the next synchronizing pulse arrives to permit the gas discharge device to be actuated thereby, it is nevertheless sufficiently positive in the middle of the interval between successive pulses to exclude the undesired double frequency horizontal pulse occurring between the desired synchronizing pulses and represented in the figure by the middle pulse of the group shown at 12. It will be understood however that the resonant frequency to which the circuit 13-14 is tuned is not particularly critical and may vary rather widely depending upon circumstances.

Although specific reference has been made to the application of the invention to the horizontal deflecting circuit of a television receiver in which it is desired to exclude certain of the double frequency horizontal pulses, it should be understood that the invention is not restricted to this application but may also be used in connection with the vertical deflecting system where it will operate to exclude noise. Furthermore, it will be understood that invention is not to be restricted to the specific impedance combinations herein shown and described for developing in the cathode circuit of the gas discharge device the desired quenching voltage. Other impedance combinations will occur to those skilled in the art suitable for obtaining the results desired in accordance with the principles herein set forth.

I claim:

20. 1. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
25. 2. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and means comprising a resistor and a condenser connected in parallel in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
30. 3. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
35. 4. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and means comprising a resistor and a condenser connected in parallel in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
40. 5. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
45. 6. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and means comprising a resistor and a condenser connected in parallel in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
50. 7. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
55. 8. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and means comprising a resistor and a condenser connected in parallel in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
60. 9. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
65. 10. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.
70. 11. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.

developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and a resistor and a condenser connected in parallel in the grid-cathode circuit of said gas-discharge device, said resistor-condenser combination having a time constant of the order of magnitude of the intervals between successive desired pulse signals and being adapted to respond to a pulse of current produced through said device in response to one of said desired pulse signals, for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.

4. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and means comprising a parallel resonant circuit included in the grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.

5. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and a parallel resonant circuit included in the grid-cathode circuit of said gas-discharge device, said resonant circuit being tuned to a frequency lower than that at which said desired pulse signals occur and being adapted to respond to a pulse of current produced through said device in response to one of said desired pulse signals, for developing in said grid-cathode circuit

5 a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.

10 6. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent, and impedance means connected in the grid-cathode circuit of said gas-discharge device and responsive to a pulse of current produced therethrough in response to one of said desired pulse signals for developing in said grid-cathode circuit a voltage impulse of substantially greater duration than the current impulse producing it whereby it is effective during a substantial portion of the interval between said desired pulses to prevent the actuation of said gas-discharge device by undesired pulse signals.

15 7. In a television system, apparatus for generating deflecting waveforms, comprising a condenser across which said deflecting waveform is developed, means including a source of voltage for charging said condenser, means including a grid-controlled gas-discharge device having at least an anode, a cathode and a control grid for discharging said condenser in response to pulse signals applied to the grid-cathode circuit of said device, a source of desired and undesired pulse signals coupled to said grid-cathode circuit, said desired pulse signals being substantially periodically recurrent and said undesired pulse signals including pulses of amplitude comparable to said desired pulses, occurring in the intervals between said desired pulses and substantially equally spaced with respect to adjacent desired pulses, and impedance means connected in grid-cathode circuit of said gas-discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is substantially dissipated prior to the occurrence of said next pulse signal, said voltage being of sufficient magnitude during said portion of the interval to substantially prevent the actuation of said gas-discharge device by said undesired pulse signals.

20 8. In a television system, apparatus for generating deflecting waveforms, comprising a condenser across which said deflecting waveform is developed, means for alternately charging and discharging said condenser, said means including a grid-controlled space discharge device having at least an anode, a cathode and a control grid and being adapted for actuation by pulse signals, a source of desired and undesired pulse signals coupled to the grid-cathode circuit of said device, said desired pulse signals being substantially periodically recurrent, and impedance means con-

nected in the grid-cathode circuit of said space discharge device and responsive to a pulse of current produced therethrough in response to one of said desired pulse signals for developing in said grid-cathode circuit a voltage which persists throughout a substantial portion of the interval between said desired pulse signal and the next succeeding desired pulse signal but which is sub-

stantially dissipated prior to the occurrence of said next pulse signal, said voltage being of sufficient magnitude during said portion of the interval to substantially prevent the actuation of said space discharge device by said undesired pulse signals.
